C. D. BONSALL

CAR ROOF

Filed Jan. 18, 1922

UNITED STATES PATENT OFFICE.

CHARLES DAVID BONSALL, OF PITTSBURGH, PENNSYLVANIA, ASSIGNEE TO P. H. MURPHY COMPANY, OF NEW KENSINGTON, PENNSYLVANIA, A CORPORATION OF PENNSYLVANIA.

CAR ROOF.

Application filed January 18, 1922. Serial No. 530,079.

To all whom it may concern:

Be it known that I, CHARLES DAVID BONSALL, a citizen of the United States, and a resident of the city of Pittsburgh, county 5 of Allegheny, and State of Pennsylvania, have invented a new and useful Improvement in Car Roofs, of which the following is a specification.

This invention relates to car roofs of the 10 all-steel riveted-up type wherein self supporting roof sheets extend from side plate to side plate and have their eaves ends rigidly secured thereto and have their side margins overlapped and rigidly secured together.

One of the principal objects of the present invention is to increase the strength and 15 rigidity of the roof by improving the sectional shape of the lapped portions of adjacent sheets. Another object is to simplify the operation of pressing the sheets. Other objects are to reduce the weight of the roof, to simplify the construction thereof and to 20 reduce the cost thereof. The invention consists principally in the construction herein-after described; and it also consists in the 25 combinations and arrangements of parts hereinafter described and claimed.

In the accompanying drawings, which 30 form part of this specification and wherein like symbols refer to like parts wherever they occur,

Fig. 1 is a plain view of the end portion 35 of a car roof embodying my invention;

Fig. 2 is an enlarged transverse section through one half of the roof on the line 2-2 in Fig. 1;

Fig. 3 is a longitudinal section along the 40 ridge line of the roof on the line 3-3 in Fig. 1;

Fig. 4 is a detail cross-section through one of the lap-joints on the line 4-4 in Fig. 1;

Fig. 5 is a cross-section through one of the joints at the side plate, the section being 45 taken on the line 5-5 in Fig. 1; and

Fig. 6 is a cross-section through the side plate of the car, showing a modified form of eaves construction.

The roof shown in the accompanying 50 drawings comprises transversely arranged load-sustaining roof sheets 7, which extend from eaves to eaves of the car. The roof sheets are supported at their eaves ends on the outwardly projecting uppermost flanges

of angle-bar side plates 8 and are rigidly 55 secured to said flanges by rivets 9. The eaves of the sheets are provided with depending eaves flanges 10, which overhang the outer edges of the top flanges of the side plates 8. The roof sheets are assembled 60 by lapping their side marginal portions to form lap-joints 11; and the lapped portions are rigidly secured together by rows of rivets 12.

The roof sheets slope upwardly from the 65 eaves towards the ridge and the overlapping marginal portion of each sheet is formed into a raised rib A. Each of these ribs comprises an upstanding web portion 13 having a lateral flange 14, which extends 70 outwardly with relation to the body of the sheet, whereby the top of the rib is offset above the plane of the body of the sheet.

The web portion of the rib at one side 75 margin of each sheet gradually diminishes in height from the ridge towards the eaves and the surplus metal gained thereby, by reason of the sheet being pressed from a blank of uniform width, is turned down over the outer edge of the flanged portion 14 of 80 the rib in the form of a depending flange 15. Thus, the ribs, which are of inverted L-shaped section at the ridge, gradually change into inverted channel shaped sections on opposite sides of the ridge. As 85 the web portions of the ribs diminish in depth from the ridge towards the eaves, there is a corresponding increase in the depth of the depending flange 15 in the same direction. The depending flange 15 of each 90 rib, by reason of the gradually increasing depth thereof, reaches the plane of the body of the sheet at points preferably located inside of the inner faces of the side plates and is turned out outwardly in the plane 95 of the sheet to form an outwardly extending lateral base flange 16. These flanges, by reason of the gradually decreasing height of the ribs, gradually increase in width as they approach the side plates and are secured to 100 the body portions of adjacent sheets and to the upper flanges of the side plates by rivets 9.

As shown in Figs. 1 and 2, the stiffening 105 ribs are turned down, as at 17, over the side plates to prevent cinders from entering the open ends of the hollow box-girder portions formed by the channel shaped eaves end

portions of said ribs. As shown in Fig. 6, the ribs terminate short of the eaves and have open ends for the escape of cinders. With this arrangement, the down-turned portions of the sheets are the only part of the roof subject to damage in the event of side-swiping, thus leaving the stiffening ribs intact.

As shown in Figs. 1 and 2 of the drawings, the tops of the ribs are preferably disposed horizontal to provide horizontal seats for running boards 18. At the ends of the car, running board saddles 19 are secured to end plates 20 of the car by rivets 21, which also secure the outer marginal edges of the endmost sheets to the top-flanges of the end plates.

The forming of the sheets with stiffening ribs at one side margin only permits the use of a die of smaller size and less weight than would be required for simultaneously pressing a rib in each margin of the sheets. The sheets are assembled by lapping the plain margin of one sheet and the ribbed margin of an adjacent sheet. Thus, the margins of adjacent sheets are secured together by plain lap-joints; and these joints are strengthened by the ribs A which function as carlines to withstand vertical roof loads and horizontal service strains. The forming of the eaves portions of the stiffening ribs into inverted channels having lateral base flanges and the securing of these base flanges to the body portions of the adjacent sheets results in a hollow box-girder section adapted to resist horizontal service strains. If desired, the running boards may be spaced above the stiffening ribs and supported from said ribs or from the body of the sheets by means of separate running board saddles. It may also be desirable to locate the stiffening ribs on the inside of the car, instead of locating such ribs on the outside of the car as shown in the drawings.

The invention is not restricted to the precise shapes and arrangements shown and described.

What I claim is:

1. A car roof comprising a plurality of roof sheets extending from eaves to eaves with their adjacent side marginal portions lapping each other and rigidly secured together along a single line located far enough from the side edge of one sheet to permit the free marginal portion thereof beyond said line to be formed into a stiffening rib whose outer edge portion is free throughout the middle portion of the roof.

2. A car roof comprising a plurality of

roof sheets extending from eaves to eaves with their adjacent side marginal portions lapping each other and rigidly secured together along a single line located far enough from the side edge of one sheet to permit the free marginal portion thereof beyond said line to be formed into a stiffening rib, the rib being of L-shaped section at the ridge and of substantially channel-shaped section at the eaves, the channel portion of a rib of one sheet cooperating with the body portion of an adjacent sheet to form a hollow box-girder eaves section.

3. A car roof comprising a plurality of roof sheets extending from eaves to eaves with their adjacent marginal portions lapping each other, the lapping portions of adjacent sheets being rigidly secured together along a single line far enough from the side edge of the upper sheet to permit the marginal portion thereof beyond said line to be formed into a stiffening rib whose outer edge is clear of the sheet adjacent thereto except at the eaves.

4. A car roof comprising a plurality of roof sheets extending from eaves to eaves with their marginal portions lapping and rigidly secured together along a single line located far enough from the side edge of the sheet that is uppermost at a joint to permit the free marginal portion thereof beyond said line to be formed into a stiffening rib, the rib having a flat portion extending horizontally on opposite sides of the ridge and constituting a direct support for running boards.

5. A car roof comprising a plurality of roof sheets extending from eaves to eaves with their adjacent side marginal portions overlapped and rigidly secured together by rivets that are located far enough from the side edge of the overlapping marginal portion of a sheet at the ridge to permit the free marginal portion of said sheet to be formed upwardly and outwardly to provide seats, running boards resting on said seats, and means located entirely outside of the car for securing said running boards to said seats.

6. A roof sheet for a car roof, said roof sheet having a strengthening rib formed in one side margin only, said rib sloping upwardly from the eaves towards the ridge and having a portion extending horizontally on opposite sides of the ridge and adapted to support the running boards of the roof.

Signed at New Kensington, Pa., this 13th day of January, 1922.

CHARLES DAVID BONSALL.
